UNITED STATES PATENT OFFICE.

OLEY R. SIMENSON AND OLAF M. SIMENSON, OF OLYMPIA, WASHINGTON.

POLE-REVERSING SWITCH AND WIRING SYSTEM.

1,006,140.

Specification of Letters Patent. Patented Oct. 17, 1911.

Application filed October 27, 1910. Serial No. 589,381.

To all whom it may concern:

Be it known that we, OLEY R. SIMENSON and OLAF M. SIMENSON, citizens of the United States, residing at Olympia, in the county of Thurston, State of Washington, have invented a new and useful Pole-Reversing Switch and Wiring System, of which the following is a specification.

It is the object of this invention to provide a pole reversing switch, the terminals of which are connected in a novel and improved manner to provide for the reversing of the current.

Another object of the invention is to provide a rotatable member, of novel and improved form, adapted to engage the terminals, and to provide novel means for holding the rotatable member both in engagement with the terminals and out of engagement with the same.

Another object of the invention is to improve generally the construction of pole reversing switches, so as to enhance their strength, and wearing qualities, and to facilitate their operation.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings,--Figure 1 is a bottom plan; Fig. 2 is a transverse section on the line A--B of Fig. 4; Fig. 3 is a transverse section on the line C--D of Fig. 4; Fig. 4 is a top plan of the base of the switch, the top being removed, and parts being omitted; Fig. 5 is a top plan of the switch, showing the top assembled with the base, the view depicting the switch as it will appear when in use; and Fig. 6 is a section detail of the top of the device.

In carrying out the invention there is provided a base 1, ordinarily circular in outline and fashioned from insulating material. This base 1 is provided with an upstanding peripheral flange 1' (see Figs. 2 and 3) to which a top 2 is threaded, as shown at 3. In the base 1 there are several counter-sunk holes 4, adapted to receive screws or the like, whereby the base 1 may be connected with a support.

The base 1 is provided with a principal terminal 5, a primary terminal 6, an intermediate terminal 10, an auxiliary terminal 8, a secondary terminal 7, and an intermediate terminal 9, disposed in the order named, around the center of the base 1, and upstanding slightly thereabove. These terminals are extended downwardly through the base 1, and are held in position by nut 60 and washer connections 11, located in recesses 12 in the lower face of the base 1. A wire or other conductor 14 unites the principal terminal 5 with the auxiliary terminal 8. A wire or other conductor 15 70 unites the primary terminal 6 with the secondary terminal 7. These conductors 14 and 15 are seated in grooves 16 formed in the upper face of the base 1, the grooves 16, after the conductors are seated therein, being filled with paraffin or the like.

There is an opening in the top 2, surrounded by a bearing collar 17 in which a stem 18 is mounted for rotation. To the upper end of the stem 18 a thumb piece 19 80 is secured by means of a set screw 20. Projecting radially from the stem 18 and located beneath the top 2 are projecting pins 21 and 21', located 90° apart. Spring pawls 22 are secured to the inner face of the top 2. 85 At their free ends, these spring pawls bear upon oppositely disposed pins, so as to limit the rotation of the stem 18. There are seats 23 in the pawls 22 adjacent their ends and these seats engage the pins 21 and 21' to 90 hold the stem 18 in predetermined positions. Referring to Fig. 6 it will be noted that, although the stem 18 may be rotated in one direction, the stem cannot be rotated in an opposite direction since the free ends 95 of the pawls 22, being below the pins when not resting thereon, will prevent such reverse rotation.

The lower end of the stem 18 is journaled for rotation in the base 1, and extends 100 through the base 1 into a recess 24 in the lower face of the base. A nut and washer connection 25, located in the recess 24, serves to hold the stem 18 in place. The stem 18 is squared as shown at 26, to engage a disk 105 27, so that the disk and the stem will rotate together. The disk 27 is ordinarily fashioned from hard rubber, although any other suitable insulating material may be used. A washer 28 rests upon the upper face of the disk 27 and surrounds the stem 18. A pin 29 or the like, is inserted through the stem

18, to hold the washer 28 and the disk 27 in place against upward movement.

In the opposite edges of the disk 7 there are grooves 30, and into these grooves 5 bridges are inserted. The bridges are of rectangular configuration, one bridge including arms 31 and 32, and the other bridge including arms 33 and 34. The bridges are held in place in the grooves 30 by means of 139 screws 35 or other securing devices suitable for the purpose. Upon the outer face of the top 2, as shown in Fig. 5, marks 36 may be made to indicate when the circuit is open through the switch, and when the circuit is 15 closed.

The device as above described may be employed under all conditions where a pole changing switch is called for. It will be found useful in the spark mechanism of internal combustion engines.

Referring particularly to Fig. 4 wherein is shown the switch of the present invention located in an electric circuit, a battery 40 appears. From the positive pole of the battery 40 a conductor 39 extends to the principal terminal 5, it being clearly discernible in Figs. 2 and 3 that all of the terminals are adapted at their lower ends for connection with conductors. From the intermediate terminal 9 a conductor 37 extends, this conductor 37 being connected to the intermediate terminal 10. It will of course be understood that in this conductor 37, any desired electrical apparatus may be positioned. From the primary terminal 6 a conductor 44 extends to the negative pole of the battery 40, the battery 40 being shown conventionally, to indicate any suitable source of electrical energy.

40 In noting Figs. 2 and 4, it will be seen that when the arm 31 of one bridge rests upon the principal terminal 5, the other arm of the same bridge, denoted by the numeral 32, rests upon the intermediate terminal 9.

45 When this bridge piece is positioned as above described, the arm 33 of the other bridge piece will rest upon the primary terminal 6, the arm 34 of the last named bridge piece resting upon the terminal 10.

50 At this point it may be stated that the bridge pieces are preferably fashioned from resilient material, so that proper contacts may be obtained.

When the bridge pieces are positioned as 55 shown in Fig. 4, the spring pawls 22 rest upon the pins 21 and hold the several arms of the bridges in place upon the terminals upon which they bear. Moreover, owing to the construction seen in Fig. 6, the rotatable member embracing the stem 18, the disk 27 and the bridges, can be rotated in but one direction only, that is, in the direction of the arrow B in Fig. 4. Supposing, therefore, that the rotatable member were 60 turned in the direction of the arrow B

through an arc of 180°, it will be seen that the arm 34 will rest upon the intermediate terminal 9, the arm 33 resting upon the secondary terminal 7, the arm 31 resting upon the auxiliary terminal 8, and the arm 32 70 resting on the intermediate terminal 10.

Presupposing that the device is disposed as shown in Fig. 4, the course of the electric current through the switch is as follows. From the positive pole of the battery 40, the current will pass through the conductor 39 to the principal terminal 5, through the arms 31 and 32 to the intermediate terminal 9, through the conductor 37 to the intermediate terminal 10, thence 75 through the arms 34 and 33 through the primary terminal 6, and thence through the conductor 44 to the battery 40. In case, however, the rotatable member has been moved through an arc of 180°, as hereinbefore pointed out, the current, coming from the battery 40 will pass to the conductor 39 to the principal terminal 5, through the conductor 14 through the auxiliary terminal 8, through the arms 31 and 32 to the intermediate terminal 10 through the conductor 37 to the intermediate terminal 9, through the arms 34 and 33 to the secondary terminal 7, through the conductor 15 to the primary 80 terminal 6, and through the conductor 44 to the battery 40. Therefore, when the parts of the device are positioned as shown in Fig. 1, the current, following the arrows A will pass through the conductor 37 in one direction, while if the rotatable member be 90 turned about through 180° as above set forth, the current will pass through the conductor 37 in a direction contrary to the arrows A; the function of the pole changing switch being thus consummated.

100 It is to be noted that when the seats 23 at the ends of the spring pawls 22 are engaged with the pins 21 in the stem 18, the circuit through the switch will be open, and in such instance, the button 19 will be positioned with respect to the marks 36, as shown in Fig. 5, thus indicating that the circuit is open through the switch.

Having thus described the invention, what is claimed is:—

115 1. A pole changing switch comprising a base; a top upon the base; terminals in the base; a stem rotatable in the top and the base and having means to engage the terminals; a spring pawl upon the top; and separate projections upon the stem with which the pawl interlocks to hold said means out of engagement with the terminals and to hold said means in engagement with the terminals, the engagement between the pawl and the projection serving to limit the rotation of the stem to a single direction only.

120 2. A pole changing switch comprising a base; a top thereon; terminals in the base; a member rotatable upon the base and pro-

vided with oppositely disposed putstanding bridges each comprising angularly disposed arms to engage the terminals; spring pawls upon the top engaging the rotatable member 5 to hold the arms in engagement with the terminals and out of engagement with the terminals.

3. A pole changing switch comprising a base; a stem rotatable therein; a disk secured to the stem and having slots in its opposite edges; spaced bridges each comprising angularly disposed arms, the bridges being engaged at their angles in the slots of the disk; securing devices engaging the disk 15 and the bridges; and terminals upon the base, with which the arms of the bridges engage.

4. A pole changing switch comprising a base; a top thereon; terminals upon the 20 base; a stem rotatable in the top and in the base; elements upon the stem to engage the terminals; angularly disposed projections upon the stem; a spring pawl secured to the top and adapted to engage the projections 25 successively, to hold said elements out of engagement with the terminals in one instance, and in engagement with the terminals in the other instance, the spring pawl being depressible to engage beneath the projections successively, whereby the rotation of 30 the stem will be limited to a single direction only.

5. In a pole changing switch, an insulating base provided with a principal terminal, an auxiliary terminal, a primary terminal, 35 a secondary terminal, an intermediate terminal between the principal and secondary terminals, and an intermediate terminal between the primary and auxiliary terminals; an electrical connection between the principal 40 terminal and the auxiliary terminal; an electrical connection between the primary terminal and the secondary terminal; and a rotatable, base supported member provided with fixed bridges, one connecting the principal terminal with the first named intermediate terminal, and the other connecting the primary terminal with the second named intermediate terminal in one position of the rotatable member; the one bridge piece connecting the second named intermediate terminal with the auxiliary terminal, and the other bridge connecting the first named intermediate terminal with the secondary terminal 45 in another position of the rotatable 50 member.

In testimony that we claim the foregoing as our own, we have hereto affixed our signatures in the presence of two witnesses.
